SEWING MACHINE

Charles F. Rubel, Chicago, Ill., assignor to Union
Special Machine Company, Chicago, Ill., a cor-
poration of Illinois

Application May 24, 1941, Serial No. 394,984

13 Claims. (Cl. 112—220)

This invention relates to sewing machines; and while it has more especial reference to overedge sewing machines of the type featured in United States Patent No. 2,133,229 granted to the present applicant on October 11, 1938, it is adaptable to other types of sewing machines for attainment of the advantages hereinafter set forth.

Due to differences in the weight and in the momentum of the reciprocating and/or oscillating elements through which movement is imparted to the stitch-forming and feeding instrumentalities in a sewing machine, to the uneven spacing of the rotary eccentric actuators for said elements circumferentially of the drive shaft, and to uneven distribution of the load on said shaft, the operation of such a machine is attended by vibrations and noises which have a limiting effect upon the speed, and hence upon the output, of the machine.

My invention has for its chief aim to overcome the above drawback with a view toward securing an improved dynamic balance which will insure quiet vibrationless operation of the sewing machine at high speeds. This objective I realize in practice, as later on more fully disclosed herein, through provision of eccentrically-weighted rotary members which are suitably located on, and circumferentially set about the shaft to counterbalance the rotating and oscillating parts. These counterbalancing members may differ in weight and may be used either alone to compensate for the uneven circumferential spacing of the rotary eccentric actuators and the uneven distribution of the loads on the shaft, or they may in addition serve to cancel out or nullify any vibrations attending the action of auxiliary counterbalance means directly associated with certain relatively heavy reciprocating or oscillating parts of the sewing machine as will also be readily understood from the subsequent disclosure.

Other objects and attendant advantages will appear from the following description of the attached drawings, wherein

Fig. 1 is a view partly in front elevation and partly in longitudinal section of an overedge sewing machine conveniently embodying my invention, the section being taken as indicated by the angled arrows I—I in Fig. 2.

Fig. 2 is a view partly in side elevation and partly in staggered vertical section taken as approximately indicated by the angled arrows II—II in Fig. 1.

Fig. 3 is a fragmentary view corresponding

generally to Fig. 1 and showing more particularly the means by which the needle and looper bars of the machine are actuated.

Fig. 4 is a detail view in elevation looking as indicated by the angled arrows IV—IV in Fig. 2, of another of the rotary counterbalancing members on the drive shaft.

Fig. 5 is a detail view in section taken as indicated by the angled arrows V—V in Fig. 2 showing one of the rotary counterbalancing members on the drive shaft of the machine.

Fig. 6 is a view like Fig. 3 with the parts in changed positions.

Fig. 7 is a detail view like Fig. 4 with the illustrated parts corresponding in position to the showing in Fig. 6.

Fig. 8 is a perspective view of one of the rotary counterbalancing members; and,

Fig. 9 is a perspective view of a trough which serves for a purpose later explained.

Briefly described, the illustrated sewing machine has an upright housing 1 in the form of a standard with a laterally projecting portion or head 2 at the top thereof. The horizontally arranged tangentially-contacting feed wheels or cups of the machine are indicated at 3, 4 in Fig. 1, and shown as secured respectively to the lower ends of vertical shafts 5 and 6 which extend upwardly through suitable journals into the head 2. A pair of intermeshing spur gears 7, 8 at the tops of the shafts 5, 6 within the hollow of the head 2 determine unison rotation of the two feed wheels 3, 4 in opposite directions as required in the feeding. The thread-carrying needle 10 of the sewing machine is secured in a holder 11 at the forward or outer end of a horizontal cylindrical bar 12 which passes through an oil-tight guide sleeve 13 in the side wall 14 of the housing 1. As in the patent hereinbefore referred to, the needle penetrates fabric passed between the feed wheels 3, 4 substantially at the point of tangency of said wheels; and cooperating with the needle in the formation of overedge stitching is a main thread-carrying looper 15 and an auxiliary instrumentality in the form of a non-thread carrying looper or spreader 16. The main looper is secured to the outer end of a carrier bar 17 which is arranged at an acute angle to the horizontal, and which passes into the interior of the housing 1 through an oil-tight guide bushing 18 in the front wall 14 of said housing.

As presently explained, the bar 17 is given endwise reciprocatory movements and also oscillatory movements about its own axis. The auxiliary looper or spreader 16 is carried at the outer

50 55

end of a separate bar 19 confined to oscillatory movement. As shown, the bar 19 is inclined in parallel relation to the main looper carrier bar 17 and passes to the interior of the housing 1 through an elongate bearing sleeve 20 set into the side wall 14 in a plane below that of said main looper bar.

The mechanism from which the needle and looper carriers 12, 17 and 19 derive their motion is enclosed in a chamber 21 in the upper part of the housing 1, which chamber is normally kept filled with lubricating oil to the level indicated at L in Figs. 1 and 2. The actuating mechanism includes a horizontal drive shaft 22 whereof the ends pass outwardly through inset bearing sleeves 23, 24 in the front and rear walls 25, 26 of the housing, as shown in Fig. 2. The needle bar 12 receives its endwise movements through a pitman or connecting rod 27 from an offset crank 28 near the center of the drive shaft 22. Secured to the drive shaft 22 immediately adjacent the bearing 24 is a rotary eccentric actuator 29, which, through a pitman 30 is connected to the lower arm 31a of a vertically arranged rocker 31. From Fig. 2 it will be noted that this rocker is mounted for free oscillation on a horizontal shaft 32 whereof the ends extend into bosses 33, 34 on the front and rear walls of the housing above the drive shaft 22, said shaft 32 being held against rotation by a set screw 35, and the ends of the bores in said bosses being closed by screw plugs 36, 37. The rocker 31 is prevented from shifting along the shaft 32 by a collar 38 which bears against the hub of said rocker at one end, the other end of said hub bearing against the boss 34. The upper arm 31b of the rocker 31 is coupled, by means of a pitman or connecting rod 40, with a roller clutch 41 (Fig. 1) on the shaft 6 of the feed wheel 4, with the result that, through the oscillation of the rocker 31, intermittent feed movements are imparted to the feed wheels 3, 4. Also mounted for free oscillating movement on the shaft 32 is a second rocker 42 whereof the fulcrum boss is confined between adjustable collars 43, 44 on said shaft 32. The pendent arm 42a of the rocker 42 is coupled by means of a pitman or connecting rod 46, with a second offset crank 47 in the drive shaft 22, see Figs. 3 and 6; while the upper arm 42b of said rocker is coupled, by means of a short link 49, with a sleeve 50 on the carrier bar 17 for the main looper 15. The sleeve 50 is held against axial shifting on the bar 17 between a collar 51 and a short ball arm 52, both of which are fixedly secured to said bar. A pitman 53 connects the ball arm 52 with another rotary actuator in the form of an eccentric 55 on the drive shaft 22. Through the connections just described, it will be apparent that both endwise reciprocatory movements and oscillatory movements are imparted to the bar 17 as required to predetermine proper cooperation of the main looper 15 with the needle 10 and the auxiliary looper or spreader 16 in a manner well understood. The bar 19 for the auxiliary looper or spreader 16 is oscillated through coupling of a short ball arm 56 at its inner end by means of a pitman or connecting rod 57, with another eccentric actuator 58 positioned between the eccentrics 29, 55 on the drive shaft 22. Also mounted on the drive shaft 22 is a disc 59 which dips into the oil supply within the chamber 21 of the housing 1, and which, by its rotation, disperses oil within said chamber to automatically lubricate the various parts of the actuating mechanism.

It is to be noted from the drawings that properly coordinated action of the feeding and stitch-

forming instrumentalities of the machine requires that the rotary actuators from which said instrumentalities derive their movements be unequally placed circumferentially of the drive shaft 22.

5 As a consequence of this, and due to the presence of so many oscillating and/or reciprocating parts of different bulk and momentum in the actuating mechanism, and to the varying loads at different points along the shaft, the operation of the machine would ordinarily be attended by considerable vibration and noise at the usual speeds.

As hereinbefore pointed out, the purpose of the present invention is to overcome these drawbacks with a view toward attaining smoother and quieter operation of such a machine so that it can be run at which higher speeds with attendant corresponding increase in output therefrom. Contributory to the attainment of these advantages is the provision of counterbalancing members 65, 66 which are shown as being incorporated, respectively, with driving wheels 67, 68 on the opposite protruding ends of the shaft 22. The wheels 67, 68 are similar in construction and provided, respectively, with plain surfaced annular hand grasp portions 69 and 70 and with circumferentially grooved pulley portions 71 and 72 so that either one of them may be utilized for manual or power driving of the machine. In the illustrated instance, the rotary counterbalancing members 65 and 66 are made as separate elements of annular configuration to fit within the hollows of the wheels 67 and 68, and are provided with central bosses 73 and 74. These bosses engage over the hubs 75 and 76 of the wheels 67 and 68 and connect to the rims of the members by radial webs 77 and 78 which differ in mass and weight and which constitute counterbalances in eccentric relation to the shaft axis. The wheels 67 and 68 are secured to the shaft 22 by set screws respectively designated 79 and 80, and the counterbalance members 65 and 66 secured to the wheels by screws 81 and 82.

As already pointed out the looper bar 17 has both an oscillatory movement and an endwise movement. The limits of travel of the endwise movement are indicated in Fig. 3 where the looper bar 17 is shown in its extreme right-hand position, and in Fig. 6 where the said bar is shown in its extreme left-hand position. It will thus be seen that at each end of its travel the looper bar undergoes a reversal of direction which produces vibration. In order to directly counteract such vibration at least in part, I have provided a counterweight 83 at the lower end of the rocker 42 which counterweight also undergoes a change of direction at each end of the travel of said arm. The reversals of direction of the counterweight 83 and the looper bar 17 are simultaneous in point of time but are 180° apart with respect to the direction of reversal. Thus when the counterweight 83 is changing direction from left to right the looper bar 17 is changing direction from right to left. However, while the horizontal vibration resulting from the action of the looper bar 17 is thus substantially reduced, an additional vibration of smaller degree is introduced by the action of the counterweight 83 due to the fact that it is positioned at the end of the rocker arm 42 which pivots about the center 32. As a consequence of such pivoting the counterweight 83 does not travel in a path parallel to that of the looper bar 17, and hence there is set up a vertical component which introduces a secondary vibration of smaller degree when reversal of motion takes place. For the elimination of this

latter or secondary vibration as well as the vibrations set up by the other parts actuated from the shaft 22, I rely upon the rotary counterbalancing members 65, 66 associated with the drive wheels 67, 68.

In connection with a cup feed sewing machine of the specific construction herein illustrated by way of example and provided with a counterweighted rocker 42, substantially vibrationless operation is obtained by placing the heavier counterbalancing member 65 in proximity to the rocker weight 83, i. e., on the right hand end of the shaft 22 as considered in Fig. 2, and by setting said counterbalancing member and the cooperative counterbalancing member 66 circumferentially of the shaft so that their weighted portions 77, 78 are respectively thirteen and a half degrees in advance of, and forty-seven and a half degrees behind the crank 47 (which operates the rocker) in the direction of rotation as shown in Figs. 4 and 5. Due to the aforescribed circumferential positioning of the counterbalancing members 65 and 66 relative to the crank 47, they attain a downward momentum at the time when the counterweight 83 reverses its motion from right to left, and an upward momentum at the time when said counterweight reverses its motion from left to right (Figs. 3-5). In the case of the right-hand counterweight 65, the momentum is relatively greater than for that of the counterweight 66 due to the larger mass involved. Thus, in addition to their modifying influence upon the action of the rocker 42, the rotary counterbalances 65, 66 also serve, when positioned on the shaft 22 as above explained, to compensate for the unbalance due to the uneven disposal of the various rotary eccentric actuators 29, 47, 55 and 58 and thereby to damp out vibrations which are ordinarily due to this cause. It is of course to be understood that the described setting of the rotary counterbalances holds only for the specific type of sewing machine herein shown and may be quite different for other types of machines where a lesser or greater number of instrumentalities are actuated from the drive shaft.

If desired, the counterbalancing members 65, 66 may be so constructed as to be independently adjustable circumferentially of the wheels 67, 68. However, in practice, after the proper preparation and setting of the counterweight members 65, 66 has once been determined by trial for a specific type of sewing machine, I prefer, for the sake of economy in assembling subsequent machines of the same type at the factory, to secure said counterweights to the wheels 67, 68 permanently in such positions in the manner illustrated in the drawings.

As another alternative the counterbalancing weights 77 and 78 may be integrally formed with the wheels 67, 68 if this should be found desirable or advantageous.

In order to prevent interference with the movement of the rocker 42 and at the same time obviate churning or breaking up of the oil in the bottom of the chamber 21, a guard in the form of a trough 84 is placed within said chamber to exclude oil from the path of the counterweight 83 at the bottom end of said rocker. As shown, the trough 84 is provided with a tongue 85 for attachment by screws 86 to the shaft bearing boss 87 on the frame wall 25; but if found to be more expedient, it may be cast integrally with the machine frame.

My invention is not to be regarded as limited

to the counterweighting of but one of the oscillating elements of the actuating mechanism in a sewing machine of the illustrated type, since, if found necessary or advantageous, the rocker 31 for the needle bar 12 may, for example, be similarly counterweighted.

Within the scope of the appended claims, the rotary counterbalances may be increased in number in accordance with special requirements of other types of machines. Moreover, in accordance with my invention, the counterbalances may be employed as the sole means of compensating for unbalance due to uneven circumferential disposal of the rotary actuators on the drive shaft as well as for the uneven distribution of the loads along the length of the said shaft.

Having thus described my invention, I claim:

1. In a sewing machine, stitch-forming instrumentalities including a needle and a cooperating looper; carrier bars respectively for the needle and the looper; a drive shaft; a rotary eccentric actuator on the drive shaft from which the needle bar derives its movements; another rotary eccentric actuator on the drive shaft operative through a rocker to reciprocate the looper bar; and means for eliminating vibration during the operation of the machine including a counterweight on the rocker, and a plurality of eccentrically-weighted counterbalancing members secured in different circumferential positions at different points along the shaft.

2. In a sewing machine, a stitch forming instrumentality and a reciprocating carrier therefor, a horizontal rotary shaft; means including a rotary actuator on the shaft and a rocker for actuating the carrier; additional rotary actuators on the shaft for actuating other moving parts of the machine differing in weight and momentum, said rotary actuators being all mounted on the shaft intermediate its ends; means for damping vibrations in the machine including a weight mass associated with the rocker and reciprocated in a path substantially parallel to the line of movement of the carrier at a corresponding rate but in opposed relation thereto, and eccentrically weighted members of different magnitude at opposite ends of the shaft differently disposed circumferentially thereof and coacting to counterbalance the several rotary actuators and the parts operated thereby.

3. In a sewing machine, a closed housing; stitch forming instrumentalities external to said housing; a drive shaft extending horizontally through oil-tight bearings in opposite side walls of the housing; an endwise reciprocating carrier bar for one of the stitch forming instrumentalities extending through an oil-tight guide bearing to the interior of the housing; means including a rotary actuator on the shaft within the housing and a rocker for actuating the carrier bar; other rotary actuators on the shaft within the housing for actuating carriers for others of the stitch forming instrumentalities differing in weight and momentum from the bar aforesaid; and means for damping vibrations in the machine including a weight mass associated with the rocker and reciprocated in a path substantially parallel to the line of movement of the reciprocating carrier bar at a corresponding rate but in opposed relation thereto; and eccentrically weighted members mounted on the opposite protruding ends of the shaft, said members being differently disposed circumferentially of said shaft and coacting to counterbalance the several rotary actuators and the parts actuated thereby.

4. In a sewing machine, a closed housing, stitch forming instrumentalities external to said housing; a shaft extending horizontally through oil-tight bearings in opposite side walls of the housing; an endwise reciprocating carrier bar for one of the stitch forming instrumentalities, extending through an oil-tight guide bearing to the interior of the housing; means including a rotary actuator on the shaft within the housing and a rocker for actuating the carrier bar; additional rotary actuators on the shaft within the housing for actuating carriers for others of the stitch forming instrumentalities differing in weight and momentum from the bar aforesaid; and means for damping vibrations in the machine including a weight mass associated with the rocker and reciprocated in a path substantially parallel to the line of movement of the carrier bar at a corresponding rate but in opposed relation thereto; and eccentrically weighted members of different magnitudes mounted on the opposite protruding ends of the shaft, said members being differently disposed circumferentially of the shaft and cooperative to counterbalance the several rotary actuators and the parts actuated thereby.

5. In a sewing machine, a closed housing; stitch forming instrumentalities external to said housing; a shaft extending horizontally through oil-tight bearings in opposite side walls of the housing; an endwise reciprocating carrier bar for one of the stitch forming instrumentalities extending through an oil-tight guide bearing to the interior of the housing; means including a rotary actuator on the shaft within the housing and a rocker for actuating the carrier bar; additional rotary actuators on the shaft within the housing for actuating carriers for others of the stitch forming instrumentalities differing in weight and momentum from the carrier bar aforesaid; and means for damping vibrations in the machine including a weight mass associated with the rocker reciprocated in a path substantially parallel to the line of movement of the carrier bar at a corresponding rate but in opposed relation thereto; drive wheels respectively mounted on the opposite protruding ends of the shaft; and eccentrically disposed weights on said drive wheels cooperating to counterbalance the several rotary actuators and the parts actuated thereby.

6. In a sewing machine, a closed housing, stitch forming instrumentalities external to said housing; a shaft extending horizontally through oil-tight bearings in opposite side walls of the housing; an endwise reciprocating carrier bar for one of the stitch forming instrumentalities extending through an oil-tight guide bearing to the interior of the housing; means including a rotary actuator on the shaft within the housing and a rocker for actuating the carrier bar; additional rotary actuators on the shaft within the housing for actuating carriers for others of the stitch forming instrumentalities differing in weight and momentum from the bar aforesaid; and means for damping vibrations in the machine including a weight mass associated with the rocker and reciprocated in a path substantially parallel to the line of movement of the carrier bar at a corresponding rate but in opposed relation thereto; drive wheels respectively mounted on the opposite protruding ends of the shaft; and eccentric weights differently disposed circumferentially of the wheels and cooperating to counterbalance the several rotary actuators and the parts actuated thereby.

7. In a sewing machine, a closed housing; stitch forming instrumentalities external to said housing; a shaft extending horizontally through oil-tight bearings in opposite side walls of the housing; a reciprocating carrier bar for one of the stitch forming instrumentalities extending through an oil-tight guide bearing to the interior of the housing; means including a rotary actuator on the shaft within the housing and a rocker for actuating the carrier bar; additional rotary actuators on the shaft within the housing for actuating carriers for others of the stitch forming instrumentalities differing in weight and momentum from the bar aforesaid; and means for damping vibrations in the machine including a weight mass associated with the rocker and reciprocated in a path substantially parallel to the line of movement of the carrier bar aforesaid at a corresponding rate but in opposed relation thereto; drive wheels respectively mounted on the opposite protruding ends of the shaft; and eccentric weights of different magnitude differently disposed circumferentially of the drive wheels and cooperating to counterbalance the several rotary actuators and the parts actuated thereby.

8. In a sewing machine, a stitch forming instrumentality; a carrier therefor; a medially fulcrumed lever having one arm thereof operatively connected to the carrier and having a counterweight at the end of its other arm; and actuating means connected to the last mentioned arm of the lever at a point between the fulcrum and the counterweight, whereby said counterweight and the carrier are contrarily reciprocated concurrently in substantially parallel paths with consequent minimization of vibration in the machine.

9. In a sewing machine, stitch forming instrumentalities including a reciprocated needle; a looper to cooperate with the needle; carriers in the form of reciprocating bars respectively for said needle and looper; a medially fulcrumed lever having one arm thereof operatively connected to one of the bars and having a counterweight at the end of its other arm; actuating means operatively connected to the last mentioned arm of the lever at a point between the fulcrum and the counterweight whereby said counterweight and said bar are contrarily reciprocated concurrently with the counterweight moving in an arc whereof the chord is substantially parallel to the line of reciprocation of the last mentioned bar, said actuating means including a rotary shaft from which said bars are operated in properly timed relation.

10. In a sewing machine, a stitch forming instrumentality and a reciprocating carrier therefor; a medially fulcrumed lever having one arm thereof operatively connected to the carrier and having a counterweight at the end of its other arm; a rotary shaft; a rotary actuator on the shaft connected to the last mentioned arm of the lever at a point between the fulcrum and the counterweight whereby said counterweight and the carrier are contrarily reciprocated concurrently in substantially parallel paths; and an eccentrically weighted member on the shaft for counterbalancing said rotary actuator.

11. In a sewing machine, a stitch forming instrumentality and a reciprocating carrier therefor; a rotary shaft; a medially fulcrumed lever having one arm thereof operatively connected to the carrier and having a counterweight at the end of its other arm; a rotary actuator on the

shaft operatively connected to the last mentioned arm of the lever at a point between the fulcrum and the counterweight, whereby said counterweight and the carrier are contrarily reciprocated concurrently in substantially parallel paths; additional rotary actuators on the shaft for operating other moving parts which differ in weight and momentum; and eccentrically weighted members differently disposed circumferentially of the shaft and operative to counterbalance the several rotary actuators and the parts actuated thereby.

12. In a sewing machine, a stitch forming instrumentality and a reciprocating carrier therefor; a horizontal rotary shaft; a medially fulcrumed lever having one arm thereof operatively connected to the carrier, and having a counterweight at the end of its other arm; a rotary actuator on the shaft operatively connected to the last mentioned arm of the lever whereby said counterweight and the carrier are contrarily

reciprocated concurrently in substantially parallel paths; additional rotary actuators on the shaft cooperating with other moving parts of the machine which differ in weight and momentum, said rotary actuators being mounted on the shaft intermediate its ends, and eccentrically weighted members respectively at opposite ends of the shaft and differently disposed circumferentially thereof coacting to counterbalance the several rotary actuators and the parts actuated thereby.

13. The invention according to claim 8, in which the weight of the counterweight is substantially equal to that of the carrier, and in which the connection between the lever and the carrier and the connection between the actuating means and the lever are substantially equidistant from the fulcrum of the lever for movement of the counterweight and the carrier through substantially the same distances.

CHARLES F. RUBEL.
